UNITED STATES PATENT OFFICE.

WILLIBALD TRINKS, OF PITTSBURGH, PENNSYLVANIA, ASSIGNOR, BY MESNE ASSIGNMENTS, TO NATIONAL BRUSH WASHING MACHINE COMPANY, OF PITTSBURGH, PENNSYLVANIA, A CORPORATION OF DELAWARE.

WASHING-MACHINE.

1,187,478.

Specification of Letters Patent. Patented June 13, 1916.

Application filed September 28, 1915. Serial No. 53,003.

To all whom it may concern:

Be it known that I, WILLIBALD TRINKS, a citizen of the United States, and residing in the city of Pittsburgh, in the county 5 of Allegheny and State of Pennsylvania, have invented or discovered new and useful Improvements in Washing-Machines, of which the following is a specification.

My invention consists in certain new and 10 useful improvements in rotary washing machines, more especially relating to means for preventing the garments or other washing from becoming wrapped or twisted about the backing roll which serves to hold 15 the garments against the rotary brush during the washing operation.

More particularly, my invention comprises a stripper blade resiliently held against the face of the backing roll and 20 carried by the mounting of said roll, so as to move in unison with and bear constantly against said roll.

Other novel features of construction and arrangement of parts will appear from the 25 following description.

In the accompanying drawings, Figure 1 is a side elevation of a washing machine embodying my invention; Fig. 2 is a broken partial plan view of the same; Fig. 3 is a 30 broken elevation showing the stripper blade dismounted, and Fig. 4 is an end elevation of the same with the mounting thereof shown in dotted lines.

The following is a detailed description 35 of the drawings.

A represents one of the ends of the washing machine frame, the two ends being similar in design, and having journaled between them the rotary washing brush B provided 40 with radial bristles 1. Said brush is power-driven, but as the method of applying rotary movement to the brush is not a part of the present invention, the same is not shown.

C is the backing roll held resiliently against the brush B, the ends of said roll being supported from the frame in the following manner. As both ends of the roll are supported in the same manner, I will 45 describe the mounting of one end as characteristic.

2 is a depending link whose upper end is pivotally secured to the upper portion

of the frame A and whose lower end is pivotally secured to the outer end of a rod 55 3 which extends through a hole in the vertical flange 4 of the frame and has its inner end threaded to receive a washer and nut 5. A helical spring 6 is mounted on the rod 3 between said flange and said 60 washer, the tension of which spring may be adjusted by means of the nut.

The axle ends 7 of the roll C are journaled in sockets or boxes 8 on the inner faces of the links 2 intermediate of the ends of the 65 latter. It is evident that by this means the backing roll is held resiliently against the rotary brush with a force which may be adjusted by regulating the nuts on the inner ends of the rods 3. The backing roll may 70 be forced away from said brush to permit varying thicknesses of garments to pass through the machine, the two ends of the roll being enabled to move independently, owing to their individual mountings. 75

D is the stripper blade, having an upper beveled edge which fits flat against the face of the roll C below its line of contact with the rotary brush. The ends of said blade are riveted or otherwise secured to the upper 80 arms of angle brackets E which are pivotally connected at their angles, as by means of bolts 9 to brackets 10 on the lower ends of links 2. The lower arms of the angle brackets E are provided with seats to receive and contain the lower ends of helical springs 11 whose upper ends bear against the projections 12 on the inner faces of the 85 links 2.

It is thus evident that the beveled edge of 90 the blade D is held resiliently against the face of the roll C at all times, as the blade is mounted in unison with said roll and moves therewith at all times. The surface of the roll is of hard unyielding material, 95 so that it does not become grooved by contact with the brush bristles, so that no circumferential depressions appear which might catch the garments, nor can buttons or other hard articles carried by the garments sink into the surface of the roll and thus enter under the stripper blade. 100

Should, however, a garment gain entrance between the roll and the stripper, no injury to the garment will result, as the mounting 105 of the stripper is outside of the ends of the

roll, out of the way of the garments, and a smooth, regular surface is presented. The stripper is held in constant contact with the roll throughout its length, so that as the 5 stripper in time wears down, its edge will always be kept in close contact with the roll.

As the washer is intended to be power-driven at considerable speed, it is evident that my improved stripper is of great value 10 in preventing accidental stoppage of the machinery and destruction of garments.

What I desire to claim is—

1. In a washing machine the combination of a frame, a rotary brush roll journaled in 15 said frame, a swinging support mounted on said frame, a backing roll journaled in said support and held resiliently against said brush roll, a stripper blade having its ends journaled in said swinging support, and 20 springs connecting said blade with said swinging support whereby said blade is held resiliently against the surface of the said backing roll, as and for the purpose set forth.
2. In a washing machine the combination 25 of a frame, a rotary brush roll journaled in said frame, a pair of links pivotally at-

tached at their one ends to said frame, a backing roll having its ends journaled in 30 said links and held resiliently against said brush roll, a stripper blade having its ends journaled in said links, and a spring connecting each end of said blade with one of 35 said links, whereby the edge of said blade is held resiliently against the surface of said backing roll, as and for the purpose set forth.

3. In a washing machine the combination of a frame, a brush roll journaled in said frame, a pair of links pivotally attached at 40 their one ends to said frame, a backing roll having its ends journaled in said links intermediate of the ends of the latter and held resiliently against said brush roll, a stripper blade having its ends journaled in said 45 links adjacent to the free ends of the latter, angular brackets on said stripper blade, and springs interposed between said brackets and said links whereby said blade is pressed 50 resiliently against the surface of said backing roll, as and for the purpose set forth.

Signed at Pittsburgh, Pa., this 24th day of September, 1915.

WILLIBALD TRINKS.
